DESIGN FOR A FINGER RING

Felix P. Kinsley, St. Louis, Mo.

Application October 10, 1938, Serial No. 80,348

Term of patent 14 years

To all whom it may concern:

Be it known that I, Felix P. Kinsley, a citizen of the United States, residing at the city of St. Louis, State of Missouri, have invented a new, original, and ornamental Design for a Finger Ring, of which the following is a specification, reference being had to the accompanying drawing, forming part thereof.

The figure is a perspective view of a finger ring

showing my new design. The dominant feature of my design resides in the arrangement of a semi-precious stone, of the contour shown, and an initial element on the face and side respectively, of the finger ring, substantially as shown.

I claim:

The ornamental design for a finger ring, as shown and described.

FELIX P. KINSLEY.
